UNITED STATES PATENT OFFICE.

WALTER L. MAJORS, OF ST. LOUIS, MISSOURI.

OIL-STOVE.

1,331,162.

Specification of Letters Patent. Patented Feb. 17, 1920.

Application filed February 10, 1919. Serial No. 276,030.

To all whom it may concern:

Be it known that I, WALTER L. MAJORS, a citizen of the United States, residing at the city of St. Louis, in the State of Missouri, 5 have invented certain new and useful Improvements in Oil-Stoves, of which the following is a specification.

This invention relates to improvements in heating devices adapted for burning oil, and 10 has for its object to provide a device of the character described that is simply and economically constructed and that may be safely operated.

Another object is to provide an improved 15 burner for an oil stove that will consume fuel economically, and will be substantially odorless.

Other objects and the advantages of this 20 invention are hereinafter described and are set forth in the claims.

In the accompanying drawings forming part of this specification, in which like numbers of reference denote like parts wherever they occur,

25 Figure 1 is a side elevation looking at the oil tank and burner casing of the device of this invention, one of the forms of removable heater covers being shown in place; and

30 Fig. 2 is a vertical sectional view of Fig. 1, with the heater cover removed.

Any suitable fuel oil 1, supplied under 35 pressure from any suitable source, such, for instance, as reservoir tank 2, is conveyed under pressure through filter chamber 3, which chamber, with any suitable filtering medium adapted for permitting oil to flow therethrough, but tending to obstruct the 40 passage of and retain foreign substances in the oil, particularly such as are not in solution, thence through tube 4 and auxiliary filter chamber 5, which is also provided with a filtering medium of any suitable character, thence through tube 6 to coil 7 or the like, where said oil is vaporized, as hereinafter described, said vaporized oil flowing from coil 7 to burner 8. Tank 2 may have an oil inlet 9 provided with plug 10 or the like, and the oil 1 in tank 2 may be placed under pressure 45 by any suitable means, such, for instance, as by means of hand-operated air compressor 11 of well-known construction

adapted to communicate with the interior of tank 2 above normal oil surface level by means of valve 12 of well-known construction. For conveniently shutting off and for regulating or controlling the flow of oil from tank 1 to coil 7, a valve, such, for instance, as needle-valve 13, may be provided in operative connection with any suitable 55 part of the oil supply line, it being of course, understood that either or both filter chambers 3 and 5 may be provided in said oil line, or additional filter chambers, not shown, may be provided in said oil line. 60

Casing 14 may be mounted on oil tank 2, as shown in the drawings, and a plurality of bolts 15 may be provided, said bolts being adapted to connect said casing and said tank firmly together, the heads 70 of said bolts being adjacent the under side of flange 16 borne by the reinforcement 17, and the screw-threaded ends of said bolts extending through appropriate holes in flange 18 forming the upper rim of casing 14, 75 nuts 19 being adapted for the well-known purpose of conveniently assembling and disassembling the parts associated together by means of the said bolts, said bolts being adapted intermediate their ends to be mounted, as shown in Fig. 1, through appropriate openings in flange 20 borne by the bottom of casing 14. A spacing casing 21 may be provided, mounted on the portion of each bolt 80 15 intermediate flange 18 and flange 20. 85

Spider 22 may have flanged rim 23 adapted to seat on shoulder 24 of flange 18, to support the spider in the top of casing 14, as best seen in Fig. 2, internally screw-threaded sleeve 25, axially borne by spider 90 22, being adapted to engage one end of screw-threaded pin 26, the other end of said pin bearing a screw head 27, which head is adapted to engage the under side of centrally-bored flame-buffer disk or plate 28, 95 upon which plate is mounted buffer body 29, said buffer body being appropriately bored to permit the head end of pin 26 to be mounted therethrough, as shown in Fig. 2. Vaporizing coil 7 may be a spiral coil, as 100 shown in the drawing, and is so disposed that buffer plate 28 and buffer body 29 may be adjusted a desired spaced relation to burner 8, by means of adjusting screw-

threaded pin 26 in sleeve 25, upwardly and downwardly between the space surrounded circumferentially by the convolutions of said coil, the jet outlet of burner 30 being disposed substantially axially of said circumferentially surrounded space and below same and substantially on a line with the axial center of said sleeve 25 and said plate 28 when the parts are mounted in operative position shown in Fig. 2.

The operation of the device thus far described may now be explained. Tank 2 having been partially filled with fuel oil 1 through intake 9, and plug or valve 10 having been adjusted to closing position in intake 9, air pump 11 may be operated to force air into tank 2 to exert any desired pressure against oil 1 in said tank 2, and, under said pressure, oil will pass from tank 2 up through filter 3 to valve 13, and, said valve having been moved to any adjusted open position, the oil will flow thence to auxiliary filter 5, thence to coil 7 and into burner 8, whereupon the flame of a torch or the like having been applied to said burner and coil through either of two door openings 33 in casing 14, each of which door openings may be provided with a sliding door 34 of well-known construction, said torch flame or the like will initially volatilize oil in said burner 8 and said coil 7, and ignite said volatilized oil as same escapes through jet opening 30 in said burner. The torch flame may then be withdrawn, and, buffer plate 28 and buffer body 29 borne thereby having been adjusted to a suitable distance from burner 8, to establish satisfactory conditions for effective combustion of volatilized oil ignited at jet opening 30, the heat of said combustion will volatilize more oil as same flows under pressure into the coil, thus automatically continuing the supply of volatilized oil to the burner for combustion at jet opening 30 as long as valve 13 is in open position and as long as oil flows to said coil under pressure from the source of oil supply. Moreover, while burner 8 functions and combustion thereat continues, the resulting heat within casing 14 tends to radiate to the compressed air and the oil in tank 2, thus heating both and tending to expand each against the other and, therefore, increasing the intensity of the pressure under which the oil is forced to coil 7 or at least compensating to some extent for the decrease of air pressure that would otherwise normally occur as the air space within tank 2 increases with the evacuation of oil therefrom in use. Furthermore, this construction and arrangement of parts provide for substantially perfect combustion of the volatilized oil, and avoids the bad odors so common in many oil-burning devices.

It will be observed that plate 28 and body

29 comprise a flame buffer piece in two parts, 65 and this construction substantially adds radiating surface for radiating heat from said buffer piece, as a very slight air space is provided between said plate 28 and said body 29, whereby the advantage is obtained that 70 the plate 28, having less volume than body 29, is heated first, and quickly provides radiation to assist in volatilizing oil in coil 7.

Having thus described this invention, I hereby reserve the benefit of all changes in 75 form, arrangement, order, or use of parts, as it is evident that many minor changes may be made therein without departing from the spirit of this invention or the scope of the following claims.

I claim:

1. A heating apparatus of the character described consisting of an oil tank, an air pressure member communicating with said tank, a valve-controlled oil feed pipe disposed in said tank, a filtering element in said pipe, a burner casing supported on the tank, an oil delivery pipe in said casing communicating with said oil feed pipe, a filtering element in the delivery pipe, a coil connected with the delivery pipe, a burner at the terminal of said coil, and a buffer body mounted above said coil and burner, said buffer body being composed of a buffer plate and body fitting together and means for adjusting the body with reference to the coil and burner.

2. A heating apparatus of the character described, consisting of a tank for oil, a burner casing supported on said tank, 100 flanges on the tank and casing, tie rods engaging said flanges and securing the tank and casing as a unit, valved air pressure means leading to the oil tank, valved oil feeding means leading from the tank to the 105 burner casing, an oil delivery pipe communicating with said feeding means, a vaporizing coil having a burner, a spider mounted in the top of the casing, an adjusting sleeve carried by said spider, a threaded stem adjustable in said sleeve, and a buffer body connected with said stem and arranged above said coil and burner.

3. A heating apparatus of the character described, consisting of an oil tank, an air 115 pressure pipe leading to said tank, and having a pressure bulb, cock and valve, an oil feed pipe in said tank, a manually controlled valve for said pipe, a filtering element in said feed pipe, a burner casing, an oil delivery pipe in said casing in communication with the feed pipe, a filtering element in said delivery pipe, a vaporizing coil leading from the delivery pipe, a burner at the terminal of the coil, and a sectional buffer body 120 supported above said coil and adjustable with relation thereto.

4. A heating apparatus for burning oil

consisting of an oil tank having a flange at its bottom, a casing having flanges at its top and bottom and resting on the top of said tank, a spider fitting in the open top of said casing, a plurality of tie rods passing through said series of flanges to connect the tank and casing as a unit, a buffer body sup-

ported from said spider, a burner under said buffer body, a coil and means disposed in the tank and casing for feeding oil to said coil 10 and burner.

In testimony whereof I hereunto affix my signature.

WALTER L. MAJORS.
